(57) **CLAIM**

The ornamental design for a wooden soap tray, as shown and described.

DESCRIPTION

FIG. 1 is a top isometric view of the wooden soap tray of the present invention having a wood-grain exterior surface;

FIG. 2 is a second top isometric view thereof;

FIG. 3 is bottom isometric view thereof;

FIG. 4 is a front view, the rear view being a mirror image thereof;

FIG. 5 is a left-side view, the right side view being a mirror image thereof;

FIG. 6 is a top plan view thereof; and,

FIG. 7 is a bottom plan view thereof.

The wood grain pattern fragmentarily shown is understood to extend throughout the areas represented.
